UNITED STATES PATENT OFFICE.

OSCAR ROBT. CASSELL, OF NEW YORK, N. Y.

FLYING MACHINE.

1,406,344.

Specification of Letters Patent. Patented Feb. 14, 1922.

Application filed September 18, 1919. Serial No. 324,335.

To all whom it may concern:

Be it known that I, OSCAR ROBT. CASSELL, citizen of the United States, residing at New York, county of New York, and State of New York, have invented certain new and useful Improvements in Flying Machines, of which the following is a specification.

This invention relates to improvements in flying machines, particularly to dirigible gas filled machines.

The principal objects of the invention are to provide a composite, rigid, flying machine for passenger service, utilizing both buoyant means and planes to sustain the same in the air, and having a propeller operable for water navigation and additional safety means for service in the air and on the water.

These and other objects will become apparent in the description below, in which characters of reference refer to like-named parts on the drawings, in which—

Figure 1 is a longitudinal central section of my complete flying machine.

Figure 2 is a cross-section of the same taken on the plane A A of Figure 1, as indicated by the arrows.

Figure 3 is a side elevation of the complete machine.

The machine comprises a substantially cigar shaped frame of circular cross-section formed of longitudinal stringers 1 intermediately connected by a longitudinal series of vertically and transversely disposed bands or rings 2. At each end are disposed pivoted to the frame, lateral fins or vanes 3 for ascent or descent, and fixed vertical fins or vanes 4 which tend to prevent deflection of the machine from its course; a fixed vertical fin or vane is also mounted centrally of the top, as shown.

Surrounding approximately the upper three-fourths of the frame, as shown, is a substantially cigar-shaped flotation body 5 flattened at the bottom, the upper and side surfaces thereof conforming to the contour of the frame. Said body, which is made of suitable fabric or other material, provides a shield for the series of separate and independent gas bags 6 in abutting contact with each other and each provided with a nipple 7 projecting downward through the base of the body whereby the bags may be filled with gas.

Each gas bag has contained within its

lower part an air bag or ballonette 6^a having a nipple 6^b projecting through the bag 6, for the purpose of passing air therethrough. These air bags 6^a provide a belt for the machine useful to aid flotation of 60 the same on the surface of the water.

It will be understood from the foregoing description that the body forms an aerostat including a reservoir which may be filled with hydrogen or other gas lighter than air, 65 and which is thus adapted to support a large proportion of the weight of the machine in the atmosphere. The lower flat surface of the aerostat also serves the function of a supporting plane which the air strikes in the 70 travel of the machine and by its dynamic reaction thereon provides means for supplementing the buoying effect of the aerostat to sustain the entire weight of the machine and its occupants. By making the reservoir in 75 sections, the same may be conveniently replenished with gas and a new gas bag substituted for one that is imperfect within a minimum of time. Thus, in the event of leakage or damage to any section of the reservoir, the efficiency of the remaining sections will remain unimpaired.

Secured in stepped relation as shown to the frame under the aerostat are planes 8 which extend beyond the sides of the frame, 85 as shown in Figure 2. These planes are inclined upward toward their forward ends. Boat shaped cars 9 are rigidly secured to the frame at each end, and a car 10^a in the center, under said aerostat, all within the 90 enclosure of said frame. The rear car is equipped with a pushing propeller 10, and the forward car with a pulling or tractor propeller 11.

The central car is equipped with a water 95 propeller for service in driving the machine along the surface of the water. These propellers may be driven by a separate motor in each car geared to a shaft 13. Ropes or cords 13 and 14, operable from the end 100 cars, control the lateral fins or vanes 3 so as to cause ascent or descent of the machine. The cars may be enclosed, as cabins, and be provided with windows 15.

Wheels 16 are vertically resiliently mounted as at 17, in a common manner. I provide an additional resilient spring or cord 18 between the wheel shaft and the frame, to lessen the breaking off effect of the wheel supports 19 as the machine glides to 110

earth and strikes the same. Dirigible rudders 20 are mounted on the supports 19. A chain or belt 21 connects the forward wheels 16 with the motor in car 9, so that 5 the machine may be propelled on land. A cross bar 30 is mounted on the top of each support 19, so that chains or the like 31 may be attached to steer said wheels.

A central substantially cylindrical space 10 is provided between the two gas bags 6 adjacent the middle of the machine, above the car, through which a ladder 22 passes from car 10^a to the top or observation platform 23. This is useful in the event that the machine floats on the water with the cars submerged, so that the occupants may climb to safety on said platform.

The longitudinal stringers 1 are braced by series of truss-forming elements 24 pivotally secured as at 25. A runner or bridge 26 connects the end cars 9 with the center car 10^a.

A balancing weight 27, secured to an endless string or rope 28, is suspended by said 25 rope on pulleys 29. By any suitable means said rope may be moved so that said weight is passed along, as desired, to balance the machine in case of accidental longitudinal tipping thereof; or said weight may be used 30 to aid in steering the machine upward or downward by respective movement rearward or forward. Longitudinal air belts 40 are arranged at each side of the frame.

From the foregoing description it is obvious 35 that in the event of the stoppage of the motor of the machine or reduction of speed thereof, from any cause, the machine will not drop directly to the ground, but will be sustained so that it will descend 40 slowly. Should it descend on the surface of water, it is capable of proplusion therethrough and is provided with means for the

safety of its occupants in case the cars become flooded.

I claim:

1. In a flying machine, a rigid substantially cylindrical frame, a flotation body having the underside thereof flattened, a covering on said frame, a plurality of gas bags enclosed in said flotation body, an air bag contained in the lower part of each of said gas bags, a series of planes spaced longitudinally of the frame at the lower part thereof and projecting laterally therefrom on opposite sides thereof, a plurality of 50 pairs of running wheels located under said frame and connected to rotatable steering posts, rudders mounted on said steering posts; and a series of propellers, one of said pairs of wheels being rotatable in unison 55 with one of said propellers.

2. In a flying machine, a rigid substantially cylindrical frame, a flotation body having the underside thereof flattened, a covering on said frame, a plurality of gas bags enclosed in said flotation body, an air bag contained in the lower part of each of said gas bags, a series of planes spaced longitudinally of the frame at the lower part thereof and projecting laterally therefrom 65 on opposite sides thereof, a plurality of pairs of running wheels located under said frame and connected to rotatable steering posts, rudders mounted on said steering posts, and a series of propellers, one of said pairs of wheels being rotatable in unison 70 with one of said propellers, and means for 75 balancing the machine longitudinally consisting of a weight, and a longitudinally movable rope to which said weight is se- 80 cured.

In testimony whereof I have affixed my signature.

OSCAR ROBT. CASSELL.
